COMBINATION RADIATOR AND OIL COOLER

Ernest H. Panthofer, Milwaukee, Wis., assignor
to Perfex Corporation, Milwaukee, Wis., a corporation of Wisconsin

Application July 24, 1946, Serial No. 685,852

2 Claims. (Cl. 257—154)

1

This invention relates generally to radiators for cooling the jacket fluid of an internal combustion engine, and more particularly to sectional radiators providing cooling surfaces for cooling two or more fluids, for example, the jacket fluid and the lubricating oil, of an internal combustion engine.

Operating temperatures of the larger internal combustion engines used in such machinery as logging tractors and the like are so high as to require some method of cooling the lubricating oil after circulation through the engine. Formerly this was done by mounting an oil circulating radiator core just behind the regular engine jacket fluid core. This system proved to be disadvantageous in that the air passing through the oil cooling core had relatively low heat absorbing properties, having already been raised in temperature during its passage through the jacket fluid core.

A further disadvantage, in the case of tractors and similar machinery, results from the poor circulation of air between the two cores caused by the accumulation of leaves, chaff, and bark which lodge in the small space between the jacket fluid core and the oil cooling core just behind it. To relieve these and other difficulties in simultaneously cooling the jacket fluid and lubricating oil of large internal combustion engines is the primary object of my invention.

A further object of my invention is to provide a dual fluid radiator embodying sections constructed and combined in a manner affording a compact, readily separable structure.

A further object of my invention is to provide a dual fluid radiator embodying separate sections constructed and combined in a manner affording a durable and inexpensive construction, and in a manner presenting the compact appearance of a conventional single fluid unit.

A further object of my invention is to provide a dual fluid radiator utilizing but a single integral header plate at each end thereof and a unitary header tank structure detachably secured to each such plate.

A further object of my invention is to in general improve the header tank and/or header plate assemblies for both dual and single fluid units.

Other objects and advantages of my invention will become apparent from the following detailed description given in connection with the accompanying drawings, in which

Fig. 1 is a rear view of my improved radiator with cut-away portions showing separating walls

2

between the two sets of headers and the construction for circulating oil through the oil cooling section;

Fig. 2 is a top view of the radiator shown in Fig. 1 with portions cut away to better show the manner of combining two sections to form in effect a readily separable unitary structure;

Fig. 3 is a view of the right hand end of the radiator shown in Figs. 1 and 2 with a portion broken away to better show construction features of the smaller section;

Fig. 4 is a perspective view of the upper portion of a dual radiator in which the sections are not separable and are constructed with a single header plate;

Fig. 5 is an enlarged view of a portion of the structure shown in Fig. 4 with parts broken away to better show the construction;

Fig. 6 is a perspective view of a dual radiator having separate tank forming sections rigidly united to form a unitary header structure, as by soldering or brazing;

Fig. 7 is an enlarged view of a lower portion of the structure shown in Fig. 6 with parts broken away to show details of the joint construction;

Fig. 8 is a view similar to Fig. 7 illustrating a modified form of joint between header tank forming sections;

Fig. 9 is a perspective view of the lower portion of a dual radiator illustrating the manner of clamping a unitary header tank structure to an integral header plate; and

Fig. 10 is an enlarged view of a portion of the structure shown in Fig. 9 with parts broken away to illustrate a modified seal construction dividing the interior of the header tank into separate chambers.

In the form disclosed herein (referring to Figs. 1 to 3), my invention consists of an engine jacket fluid section 10 with an upper header tank 11 and a lower header tank 12. The core between the two header tanks 11 and 12 is of the conventional fin and tube type. This allows hot water to enter the inlet 13 in the upper header tank 11, flow through the core section 14 where it is cooled, and flow out through the outlet 15 in the lower header tank 12. The upper header tank 11 and the lower header tank 12 are held in abutting fluid confining relation with respect to opposite ends of the core section 14 by means of the channel member 16 and by means of the I-shaped member 17. The channel member 16 and I-shaped member 17 are attached to the above mentioned header tanks by means of bolts 18 tightened into a threaded sleeve 19 as shown

in Fig. 2. The upper header tank 11 is provided with a conventional filler spout and cap 20. In this connection it should be noted that core section 14 is provided with similar upper and lower header plates 41 which are rigidly secured to the core section in the usual manner. Plate 41 is preferably provided with bent-over marginal edge portions or flanges 42 adapted to abut adjacent outer side wall portions of the header tank, as best shown in Fig. 1 and are held in liquid sealing relation with the header tank by means of solder, as is well known in the art.

The oil cooling section 21 consists of an upper header tank forming structure 22 and a lower header tank forming structure 23. The core between these two header tank forming structures is also of the conventional fin and tube type, allowing oil flow between the upper and lower header tanks. The core section between the upper header tank forming structure 22 and lower header tank forming structure 23 is provided with similar upper and lower header plates 43 which are rigidly secured to the core section in the usual manner. Plates 43 are preferably provided with bent-over marginal edge portions or flanges 44 adapted to abut adjacent outer side wall portions of the header tank, as best shown in Figs. 1 and 3 and are held in liquid sealing relation with the header tank by means of solder, as is well known in the art. Lower header tank forming structure 23 is provided with an internal transversely extending partition member 24 having its upper edge portion disposed within an inverted U-shaped resilient member 25 which is preferably brazed or otherwise secured to the bottom or underside of lower header plate 43. The sides of the member 25 are sprung against opposite sides of the partition 24, thus providing an oil tight seal dividing the interior of the tank 23 into an inlet chamber 26 and an outlet chamber 27. The numeral 28 designates a group of dummy or blocked tubes which separate the group of active tubes connecting inlet chamber 26 with upper header tank from the group of active tubes connecting such header tank with outlet chamber 27. Chambers 26 and 27 are provided with suitable inlet and outlet connections 29 and 30 respectively. Consequently the oil or other fluid enters inlet chamber 26 through the active tubes at the right of the blocked tubes 28, flows into the upper header tank, down through the active tubes at the left of the blocked tubes 28 and into the outlet chamber 27, from which it passes through outlet connection 30.

Referring to Figs. 1 and 2, it will be noted that the lower ends of dummy tubes 28 are spaced from header plate 43 to form a transverse opening receiving a reinforcing bar 31 abutting the top side of header plate 41 immediately above resilient member 25. Bar 31 projects beyond opposite sides of the core section and is bolted at each end to the lower header tank forming structure 23 by means of bolt 32, lock nuts 33, and threaded lugs 34.

A channel member 35 is fastened to the upper and lower header tank forming structures of the oil cooling radiator 21 by means of bolts 36 and lugs 37, which are extensions of the header tank forming structures. The two sections 10 and 21 are fastened together by bolts 38 which extend through lugs 39 on the header tank forming structures 22 and 23, and through web portions 40 of the I-shaped member 17 disposed in abutting engagement with the lugs 39. This manner

of joining sections 10 and 21 allows easy replacement of either section.

Referring now to Figs. 4 and 5, another type of dual radiator construction is shown consisting of two fluid cooling sections comprising separate conventional fin and tube core sections 50 and 51, an upper header or tank structure 53 and a similar lower header or tank structure (not shown). Structure 53 comprises a single header plate 52, in general similar to the previously described header plates 41, and an integral casting or rigid fabricated structure including spaced tank forming portions 54 and 55 united by a transverse wall portion 58. Structure 53 is clamped to header plate 52 with bottom edge portions of the side walls of tank forming portions 54 and 55, and with the wall or partition portion 58 abutting marginal edge portions and an intermediate portion, respectively, of header plate 52. The securing means comprises a cap screw 56 which extends through aligned holes in wall portion 58 and plate 52 and into internally threaded holes in an underlying clamping bar 57 as shown in Fig. 5.

Referring now to Figs. 6 and 7, another type of dual radiator construction is shown consisting of two fluid cooling sections comprising separate fin and tube core sections 78 and 79, separate upper header tank forming castings 74 and 75 having inlets 76 and 77, respectively, and separate lower header tank forming castings 80 and 81 having outlets 82 and 83, respectively. Core sections 78 and 79 are provided with similar upper and lower header plates 72, rigidly secured to the core section in the usual manner. Plate 72 is preferably provided with bent over marginal edge portions or flanges similar to the header plates shown in the preceding figures. The upper and lower pairs of header tank forming castings are similar and are provided with abutting side wall portions 84 and 85 suitably united as by soldering or brazing, as indicated at 86. This construction utilizes a single integral header plate 72 disposed in abutting relation with respect to the edges of the side walls of the header tank forming castings 80 and 81. Considerable material may be saved by terminating the side wall 85 short of side wall 84 as shown in Fig. 7. Plate 72 is preferably rigidly secured to the edge of wall 84 in any suitable manner, such as by soldering or brazing, as indicated at 87.

Fig. 8 illustrates a modified construction wherein separate header tank forming structures 90 and 91, and a separate integral header plate 92, are rigidly united to form a unitary structure providing two header tanks 93 and 94. This construction is preferred where sheet metal header tank forming structures 90 and 91 are employed in place of the cast structures of the other radiator forms so far described. Header plate 92 is preferably provided with bent over marginal edge portions (not shown) similar to the header plates previously described. Sheet metal portions 90 and 91 are somewhat resilient and have outwardly extending flanges 95 and 96 which are sprung against the header plate 92. The adjacent parts of the portions 90 and 91 are soldered as at 97, forming a liquid tight seal between the two cooling sections. This same soldered joint also serves to fasten the two portions 90 and 91 to the header plate 92.

In the modified construction shown in Figs. 9 and 10 the cooling sections consist of separate core sections 103 and 104 and a single header tank

forming structure 107. Core sections 103 and 104 are provided with similar upper (not shown) and lower header plates 102 rigidly secured to the core section in the usual manner. Plate 102 is preferably provided with bent over marginal edge portions similar to the header plates previously described. The structure 107 is formed as shown in Fig. 10 with a vertically extending transverse partition 110 coacting with plate 102 to form a pair of separate adjacent header tanks or chambers 105 and 106. A liquid tight seal between the adjacent header tanks 105 and 106 is formed without the use of machined surfaces by means of an inverted U-shaped spring member disposed in capping relation with respect to the extending transverse partition 110. The legs 112 and 113 of the spring member 111 are curved as at 114 and 115 and soldered into the depressions 108 and 109. The spring member 111 is of such dimensions and resiliency that when the parts are assembled as shown in Fig. 10, member 111 is under compression during the soldering operation, thus insuring a fluid tight seal at the curved portions 114 and 115. The header structure 107 is preferably clamped to header plate 102 by means of an enforcing cross bar 116 disposed between core sections 103 and 104 in engagement with the exposed upper surface of plate 102. Bar 116 is detachably secured to structure 107 by means of a bolt 117, a lock nut 118, and an internally threaded lug 119 which is an integral part of the member 107. Chambers 105 and 106 are provided with suitable fluid outlet connections 120 and 121 respectively (shown in Fig. 9).

From the foregoing description taken in connection with the accompanying drawings, it will be readily apparent to those skilled in the art that radiators constructed in accordance with this invention provide a simplified, compact, and inexpensive construction suitable for simultaneously cooling separate fluids, for example, the jacket fluid and oil of an internal combustion engine, in an efficient manner.

In addition, it should also be apparent that certain of the features of construction and certain of the combinations of parts herein disclosed are applicable to radiators other than the dual fluid type above mentioned, and that apparatus embodying the invention may vary considerably from that herein shown and described for purposes of illustration. However, it should be understood that it is not intended to limit the invention to the exact construction and/or combinations of elements shown and described herein, as various modifications within the scope of the appended claims may occur to persons skilled in the art.

What is claimed is:

1. In a radiator of the type including a fin and tube core section provided with a tube receiving header plate covering one end thereof, an open header tank structure secured to said header plate in fluid confining relation thereto, a partition means coacting with said header plate and tank structure to form a pair of separate fluid confining chambers communicating with the adjacent ends of separate groups of tubes, a generally U-shaped resilient member secured in capping relation to one end of said partition portion to thereby form a fluid-tight seal between said fluid confining chambers, and clamping means including a clamping bar secured to said tank structure and overlying said header plate for holding said header plate, said resilient members, and said partition end firmly in abutting relationship.
2. In a radiator of the type including a fin and tube core section provided with a tube receiving header plate covering one end thereof, an open header tank structure secured to said header plate in fluid confining relation thereto, a partition portion coacting with said header plate and tank structure to form a pair of separate fluid confining chambers communicating with the adjacent ends of separate groups of tubes, a generally U-shaped resilient member having its legs secured to opposite sides of said partition portion and held in a capping relation to one end of said partition portion thereby forming a fluid-tight seal between said fluid confining chambers, and clamping means including a clamping bar secured to said tank structure and overlying said header plate for holding said header plate, said resilient member and said partition end firmly in abutting relationship.

ERNEST H. PANTHOFER.
